(57) **ABSTRACT**

A fan control system includes first and second fan control units. Each fan control unit includes a connector, a delay circuit, a switch unit, and a control circuit. Each connector is connected to a corresponding fan interface to receive a voltage signal. The delay circuit of the first fan control unit delays the voltage signal for a first period of time, and turns on the corresponding switch unit after the first period of time. The delay circuit of the second fan control unit delays the voltage signal for a second period of time, and turns on the corresponding switch unit after the second period of time. Each control circuit receives the corresponding delayed voltage signal, to start the corresponding fan. The first period of time is unequal to the second period of time.

2 Claims, 2 Drawing SheetsFIG. 1

FIG. 2

1

FAN CONTROL SYSTEM

BACKGROUND

1. Technical Field

The present disclosure relates to a fan control system.

2. Description of Related Art

There are many fans in a server system. When the fans rotate at the full speed, there is high energy consumption, so at the instant that the server system is powered on, all of the fans will rotate at the full speed, which leads to the power supplies of the server system being unstable.

BRIEF DESCRIPTION OF THE DRAWINGS

Many aspects of the present embodiments can be better understood with reference to the following drawing. The components in the drawing are not necessarily drawn to scale, the emphasis instead being placed upon clearly illustrating the principles of the present embodiments. Moreover, in the drawing, all the views are schematic, and like reference numerals designate corresponding parts throughout the several views.

FIG. 1 is a block diagram of an embodiment of a fan control system connected between interfaces of a motherboard and fans, the fan control system includes a control unit.

FIG. 2 is a circuit diagram of the control unit of FIG. 1.

DETAILED DESCRIPTION

The disclosure, including the accompanying drawing in which like references indicate similar elements, is illustrated by way of example and not by way of limitation. It should be noted that references to "an" or "one" embodiment in this disclosure are not necessarily to the same embodiment, and such references mean at least one.

Referring to the FIG. 1, an embodiment of a fan control system **100** is connected between first to third fan interfaces **210-230** of a motherboard **200** and first to third fans **310-330**, to control the first to third fans **310-330** to start at different time. The fan control system **100** includes first to third control unit **10-30**. The first control unit **10** is connected between the first fan interface **210** and the first fan **310**. The second control unit **20** is connected between the second fan interface **220** and the second fan **320**. The third control unit **30** is connected between the third fan interface **230** and the third control circuit **330**. The first to third control units **10-30** have the same circuit structure and function. The first control unit **10** is taken as an example to be described as follow.

The first control unit **10** includes a connector **11**, a delay circuit **12**, a switch circuit **13**, and a control circuit **14**. The connector **11** is connected to the first fan interface **210** to receive a voltage signal, a control signal, and a detection signal from the motherboard **200**. The connector **11** includes a control pin **111**, a detection pin **112**, and a power pin **113**. The control pin **111** and the detection pin **112** are both connected to the control circuit **14** to output the control signal and the detection signal to the control circuit **14**. The power pin **113** is also connected to the control circuit **14** through the switch circuit **13**. The delay circuit **12** is connected between the power pin **113** of the connector **11** and the switch unit **13**, to delay the voltage signal from the power pin **113** for a first period of time **T1**, and output a turning on signal to turn on the switch unit **13** after the first period of time **T1**. The control circuit **14** is connected to the first fan **310** to start the first fan **310** when the voltage signal is supplied to the control circuit **14**.

2

Referring to FIG. 2, the delay circuit **12** includes a resistor **R1** and a capacitor **C**. The switch circuit **13** includes a resistor **R2**, a first transistor **Q1**, and a second transistor **Q2**. The resistor **R1** and the capacitor **C** are connected in series between the power pin **113** of the connector **11** and ground. A gate of the first transistor **Q1** is connected to a node between the resistor **R1** and the capacitor **C**. A source of the first transistor **Q1** is grounded. A drain of the first transistor **Q1** is connected to the power pin **113** of the connector **11** through the resistor **R2**. A gate of the second transistor **Q2** is connected to the drain of the first transistor **Q1**. A source of the second transistor **Q2** is connected to the control circuit **14**. A drain of the second transistor **Q2** is connected to the power pin **113** of the connector **11**. The first transistor **Q1** is an n-type field effect transistor (FET). The second transistor **Q2** is a p-type FET.

When the motherboard **200** is powered on, the fan interface **210** outputs the voltage signal to the power pin **113** of the connector **11** to charge the capacitor **C**. A voltage at the node between the resistor **R1** and the capacitor **C** is greater than the turning on voltage of the first transistor **Q1** after the first period of time **T1**. The first transistor **Q1** is turned on. The second transistor **Q2** is turned on. The voltage signal from the power pin **113** of the connector **11** is output to the control circuit **14** through the second transistor **Q2**. The control circuit **14** starts the first fan **310** when the control circuit **14** receives the voltage signal, that is, the first fan **310** is started after the first period of time **T1**. The first period of time **T1** increases when the product of a resistance of the resistor **R1** and a capacitance of the capacitor **C** increases. The first period of time **T1** decreases when the product of a resistance of the resistor **R1** and the capacitance of the capacitor **C** decrease.

Similarly, the second fan **320** is started after a second period of time **T2**. The third fan **330** is started after a third period of time **T3**. The first to third periods of time **T1-T3** are made different by selecting different resistors and capacitors of the delay circuits of the first to third control units **10-30**. Therefore, the first to third fan **310-330** will be started at different time.

It is to be understood, however, that even though numerous characteristics and advantages of the embodiments have been set forth in the foregoing description, together with details of the structure and function of the embodiments, the disclosure is illustrative only, and changes may be made in details, especially in matters of shape, size, and arrangement of parts within the principles of the embodiments to the full extent indicated by the broad general meaning of the terms in which the appended claims are expressed.

What is claimed is:

1. A fan control system to control first and second fans to be started at different time, the fan control system comprising:
  - a first fan control unit connected between a first fan interface of a motherboard and the first fan; and
  - a second fan control unit connected between a second fan interface of the motherboard and the second fan, wherein each of the first and second fan control units comprising:
    - a connector connected to the corresponding fan interface of the motherboard to receive a voltage signal, and comprising a power pin;
    - a delay circuit connected to the power pin of the connector, to delay the voltage signal from the connector for a period of time, and output a turning on signal after the period of time, wherein the delay circuit comprises a first resistor and a capacitor, the first resistor and the capacitor are connected in series between the power pin of the connector and ground;

a switch unit connected to the delay circuit to be turned on after receiving the turning on signal, and connected to the power pin of the connector to transmit the voltage signal to the corresponding fan after being turned on, wherein the switch circuit comprises a second resistor, a 5 first transistor, and a second transistor, a gate of the first transistor is connected to a node of the first resistor and the capacitor, a source of the first transistor is grounded, a drain of the first transistor is connected to the power pin of the connector through the second resistor, a gate of the 10 second transistor is connected to the drain of the first transistor, and a drain of the first transistor is connected to the power pin of the connector; and a control circuit connected between the switch unit and the corresponding fan to receive the delayed voltage signal, 15 and to start the corresponding fan after receiving the delayed voltage signal, a source of the second transistor is connected to the control circuit; wherein the delay circuit of the first fan control unit delays the voltage signal for a first period of time, the delay 20 circuit of the second fan control unit delays the voltage signal for a second period of time, and the first period of time is unequal to the second period of time.

2. The fan control system of claim 1, wherein the first transistor is an n-type field effect transistor (FET), and the 25 second transistor is a p-type FET.
